UNITED STATES PATENT OFFICE.

JOSEPH J. MCINTYRE, OF BROOKLYN, NEW YORK.

AERIAL BOMB.

1,327,487.

Specification of Letters Patent.

Patented Jan. 6, 1920.

Application filed September 1, 1917. Serial No. 189,362.

To all whom it may concern:

Be it known that I, JOSEPH J. MCINTYRE, a citizen of the United States, and a resident of the city of New York, borough of Brooklyn, in the county of Kings and State of New York, have invented a new and Improved Aerial Bomb, of which the following is a full, clear, and exact description.

The object of the invention is to provide 10 a new and improved aerial bomb intended to be dropped from an aeroplane, dirigible or other air craft, and arranged to permit of safely handling the aerial bomb to insure positive explosion thereof as soon as it 15 strikes an object in its flight or at the expiration of a predetermined period of time. Another object is to cause the casing of the aerial bomb to break up into numerous small pieces and thus act similarly to shrapnel.

20 In order to accomplish the desired result, use is made of a casing filled with an explosive charge and provided with a tail, a percussion cap held on the said tail and extending into said charge, a plunger slidable in 25 the said tail and adapted to fire the said percussion cap, a fan, and a screw screwing in the said plunger and adapted to unscrew out of the same to release the plunger. Use is also made of intersecting grooves on the 30 inner face of the casing to fracture the latter along the grooves on the bursting of the casing to break the latter into uniformly small pieces.

A practical embodiment of the invention 35 is represented in the accompanying drawings forming a part of this specification, in which similar characters of reference indicate corresponding parts in all the views.

Figure 1 is a side elevation of the aerial 40 bomb;

Fig. 2 is an enlarged sectional side elevation of the same;

Fig. 3 is an enlarged sectional plan view of the same on the line 3—3 of Fig. 1;

45 Fig. 4 is a sectional side elevation of a modified form of a portion of the aerial bomb; and

Fig. 5 is a similar view of another modified form of a portion of the aerial bomb.

50 The casing 10 of the aerial bomb is filled with an explosive 11 in which shrapnel 12 is embedded, as plainly indicated in Fig. 2. The casing 10 is provided with a tail 13 having a tubular stem 14 and wings 15 extending therefrom, and the stem 12 is provided

with a lining 16 carrying at its lower end a percussion cap or primer 17 extending within the charge 11. In the upper portion of the lining 16 is mounted to slide a plunger 20 terminating at its lower end in a pin 21 60 adapted to pass into the percussion cap or primer 17 to fire the latter with a view to firing the charge 11 whenever the bomb strikes an object in its flight. In the plunger 20 screws a screw 22 extending through a 65 cap 23 held on the upper end of the lining 16. On the upper outer end of the screw 22 is secured a fan 24 rotating during the descent of the bomb to unscrew the screw 22 out of the plunger 20 thus releasing the 70 plunger. A light cord or similar retaining means 25 is threaded through registering apertures 26 and 27 formed in the plunger 20 and the lining 16, and this cord is broken by the downward movement of the released 75 plunger 20 at the time the bomb strikes an object in its flight, it being understood that the plunger prior to this action was released by the screw 22 screwing out of the stem. It is understood that when the bomb is dropped 80 by an aviator the fan 24 is set in motion and the screw 22 screws out of the plunger 20, but the latter is held against downward movement by the cord 25 until the bomb strikes an object in its flight so that the impact causes the plunger 20 to move downward and break the cord 25. The plunger in its descent finally causes the pin 21 to fire the percussion cap 17 and the latter fires the charge 11 whereby the bomb 90 is bursted and the shrapnel 12 scattered together with the pieces of the bursted casing 10.

In order to break the casing 10 into uniformly sized small parts, the inner surface 95 of the casing is provided with intersecting grooves 30 (see Figs. 2 and 4) to cause the casing to break along the grooves into a large number of small pieces which act the same as shrapnel 12.

100 In order to prevent the plunger 20 from turning in the lining 16, use is made of a pin 40 extending through the lining 16 into a groove 41 formed in the upper end of the plunger 20. It is understood that the pin 105 40 does not prevent the plunger 20 from dropping as the groove 41 extends to the top end of the plunger.

110 In order to allow a practically unrestricted descent of the plunger 20 within the

lining 16, the plunger is provided with a central opening 42 connected with the threaded bore in which screws the screw 22, the lower end of the opening 42 having 5 branch openings 43 at the pointed end of the plunger to allow the air in the lining 16 to pass through the opening 42 and the threaded bore after the screw 22 has screwed out of the plunger as previously explained.

10 The two diametrically opposite wings 15 are provided at their upper ends with a bail 45 to permit the aviator to conveniently handle the bomb. In order to prevent the fan 24 from accidentally rotating use is 15 made of a stop rod 50 mounted to slide in a bearing 51 secured on one of the wings 15. The bearing 51 is provided with a slot 52 through which extends a screw 53 screwing in the rod 50 to hold the latter normally 20 in uppermost position with the upper end in engagement with one of the vanes of the fan 24 thus preventing the fan 24 from rotating. Prior to dropping the bomb the rod 50 is moved downward to disengage and 25 release the fan 24.

The lower end of the casing 10 is provided with a head 60 carrying a percussion cap or a primer 61 extending into the charge 11. The percussion cap or primer 61 is 30 adapted to be fired by a pin 62 formed on the upper end of a plunger 63 terminating at its lower end in a head 64. The plunger 63 is mounted to slide in a screw 65 screwing in the head 60. The lower end of the 35 screw 65 is provided with a fan 66 set in motion on dropping the bomb to screw the screw 65 upward in the head 60. The plunger 63 is provided with a reduced portion 67 engaged by a pin 68 held on the 40 screw 65.

When the bomb is dropped the fan 66 screws up the screw 65 in the head 60 until the pin 68 abuts against the under side of the head 60 thus preventing further turning 45 of the screw 65. During this upward screwing movement of the screw 65 the pin 62 is carried within a short distance of the fulminate in the percussion cap or primer 61, and when the head 64 of the plunger 63 50 finally strikes the object then the plunger 63 is moved farther upward and the pin 62 engages the fulminate and thus fires the percussion cap or primer 61 thereby firing the charge 11. From the foregoing it will be 55 seen that should either of the two devices at the head and tail ends of the casing fail to do its work properly the other is liable to do so thus insuring explosion of the bomb.

60 The fan 66 is normally held against rotation by a rod 70 similar to the rod 50 and mounted to slide in a bearing 71 attached to the casing 10. A screw 72 screwing on the bearing 71 engages the rod 70 to hold 65 the latter in extended position, and on

loosening the screw 72 the rod 70 may be moved upward to disengage the fan 66 for the latter to rotate on releasing the bomb.

In the modified form shown in Fig. 4, the casing 80 is provided at its lower end with 70 a head 81 supporting a percussion cap or primer 82 extending within the charge with which the casing 80 is filled. In the head 81 screws a screw 83 provided at its lower end with a fan 86 adapted to rotate the 75 screw 85 during the flight of the bomb, to screw the screw rod 85 upward and into engagement with the percussion cap or primer 82 to fire the same thus causing explosion of the charge in the casing 80. It 80 will be noticed that in this arrangement the bomb is exploded at a predetermined time, that is, according to the distance the screw 85 is turned by the fan 86 until the percussion cap or primer 82 is exploded during the 85 flight of the aerial bomb.

The percussion caps or primers 17, 61 and 82 are preferably provided at their inner ends with a charge of fulminate, but instead of such percussion cap or primer an ordinary percussion cap 90 may be employed, as shown, for instance, in Fig. 5. In this case the rim 91 of the percussion cap rests on a cap 92 screwing on the inner end of the lining 16 of the tail 14. The percussion cap 95 90 is exploded by the pin 21 of the plunger 20 in the manner previously explained.

Having thus described my invention, I claim as new and desire to secure by Letters Patent:—

100

1. An aerial bomb, comprising a casing filled with an explosive charge and provided with a head, a percussion cap held on the said head and extending into the said charge, a screw screwing on the said head 105 and provided with a fan, a detonating plunger slidably in the screw and having a head adapted to strike an object, and limiting means on the said screw to limit the screwing movement thereof and that of the 110 plunger.

2. An aerial bomb, comprising a casing filled with an explosive charge and provided with a head and a tail, detonators extending 115 into the charge, one being held on the head and the other on the tail, a screw screwing in the said head and provided with a fan, a detonating head plunger slidably mounted in the said screw and adapted to fire the detonator in the head, a detonating tail plunger 120 slidably in the said tail, a screw screwing in the said tail plunger, and a fan on the said tail plunger screw.

3. An aerial bomb, comprising a casing filled with an explosive charge and provided 125 with a head and a tail, detonators extending into the charge, one being held on the head and the other on the tail, a screw screwing in the said head and provided with a fan, a detonating head plunger slidably mounted 130

in the said screw and adapted to fire the detonator in the head, a detonating tail plunger slideable in the said tail, a screw screwing in the said tail plunger, a fan on the 5 said tail plunger screw, and fragile means connecting the said tail plunger with the said tail.

4. An aerial bomb, comprising a casing filled with an explosive charge, percussion caps in the lower and upper ends of the said 10 casing and extending into the charge, a tail on the upper end of the casing and having a tubular stem, a tubular head on the lower end of the casing and having an interior 15 screw thread, a tail plunger slideable in the said stem and adapted to fire the said tail.

percussion cap, a fragile holding means holding the said tail plunger in non-firing position, a tail plunger screwing in the said tail plunger and provided at its upper and 20 outer end with a fan, a head screw screwing in the said head and provided with a fan, a head plunger slideable in the said screw and adapted to fire the said head percussion cap, 25 the said head plunger having a reduced portion, and a pin held on the said head screw and engaging the said reduced portion, the said pin being adapted to abut against the said head to limit the screwing movement of the said head screw.

JOSEPH J. McINTYRE.
